W. E. PATNAUDE.
INVERTED BOTTLE WATER COOLER.
APPLICATION FILED JUNE 9, 1910.

1,009,437.

Patented Nov. 21, 1911.

UNITED STATES PATENT OFFICE.

WILLIAM E. PATNAUDE, OF MERRIMAC, MASSACHUSETTS, ASSIGNOR TO ATWOOD L. BOGGS, OF DORCHESTER, MASSACHUSETTS.

INVERTED-BOTTLE WATER-COOLER.

1,009,437.

Specification of Letters Patent.

Patented Nov. 21, 1911.

Application filed June 9, 1910. Serial No. 566,013.

To all whom it may concern:

Be it known that I, WILLIAM E. PATNAUDE, a citizen of the United States, residing at Merrimac, in the county of Essex and State of Massachusetts, have invented certain new and useful Improvements in Inverted-Bottle Water-Coolers, of which the following is a specification, reference being had therein to the accompanying drawing.

10. This invention relates to improvements in inverted bottle water coolers, and the present improvement pertains to the manner of supporting the inverted bottle, in which the mouth of the bottle enters a receiving receptacle or vessel located within a cooling chamber, to cause the flow of water from the bottle to be controlled by the periodical withdrawing of cooled drinking water from the receiving receptacle or vessel.
20. The object of the present improvement is to so construct and arrange the cover; the top of the receiving receptacle, and an intervening bottle supporting member, that a closure is effected between the receiving receptacle or vessel, the bottle and the cooling chamber, to prevent any air supply to the bottle from the cooling chamber when water flows from the bottle.

In the accompanying drawing: Figure 1 is a side elevation (partly in section) of a cooler embodying the present improvement. Fig. 2 is a vertical sectional view of one form of an intervening bottle supporting member. Fig. 3 is a similar view of another form of intervening bottle supporting member.

In carrying out the present improvement, an outer or inclosing case 1 is provided, in which is placed a liquid receiving receptacle 2, which may be of any form, so long as it is so constructed and arranged that a cooling space or chamber 3 is formed there around. In the form here shown this space is made sufficiently large to receive broken or "cracked ice". A cover or top 4 is provided for the case 1, and preferably this cover is removable. The cover 4 has an opening 5 which registers with the mouth or open top 6 of the receiving vessel 2. A bottle 7 is inverted, and has its neck passing through the cover into the receiving receptacle 2, substantially as shown, and its mouth 8 is sealed by the liquid 9 in the receptacle 2. Liquid is drawn from the receiving vessel 2 through a suitable faucet 10, which passes

through the inclosing case 1 and communicates with the interior of the vessel 2. When liquid is drawn from the vessel 2 its level is lowered, and when the liquid level falls below the bottle mouth 8, air passes into the bottle and liquid is permitted to flow therefrom until the level of the liquid in the vessel 2 reaches the bottle mouth 8 and seals it. Cooling liquid is therefore periodically drawn from the vessel 2, and periodically flows from the bottle, the flow of cooled liquid from the vessel 2, controlling the supply or flow of uncooled liquid from the bottle. From this it will be understood that air passes into the bottle when liquid flows therefrom, and the present improvement pertains to the means for causing the air for the bottle to be supplied from outside of the cooling chamber, and to prevent it from being supplied from the cooling chamber 3. This improvement is effected by providing a combined bottle supporting and closing member at the junction of the top of the vessel 2 and the wall of the opening 5 of the cover 4. As here shown this is accomplished by having the top of the vessel 2 in approximately a horizontal plane with the edge wall of the opening 5 of the cover 4, and providing one of the members with a seat for the bottle supporting member 11 or 11^a. This seat is here shown as formed in the cover, and comprises an annular recess 12 in which the member 11 is placed. However, the construction of the parts may be varied without departing from the scope of the present improvement, the essential feature of which is that the member 11 forms a closure for the junction of the top of the receiving vessel 2 and the wall of the opening 5 in the cover 4, for the purpose described. This closure or member 11 is formed of some material which is more or less elastic; to more effectively close the opening at the said junction, and is preferably composed of rubber. In the arrangement here shown, the member 11 in addition to forming a closure as aforesaid, performs the additional function of supporting the bottle. This arrangement affords a yielding seat for the bottle which prevents the liability to breakage when placing the bottle in position, (especially when large five gallon bottles are used) and the weight of the bottle and its contents on the member 11 causes it to more effectively close the joint or open-

ing at the junction of the parts previously referred to.

In Figs. 1 and 2, the underside of the member 11 is provided with an annular groove *a*, which forms a yielding downwardly and inwardly projecting flange *b*, which yields under the weight of the bottle and its contents, as shown in Fig. 1, thus forming a groove into which the extreme upper edge of the mouth or top 6 of the vessel 2 fits, which adds to the effectiveness of the closure. However, a practical closure can be effected by having the member 11 of the cross-sectional shape shown in Fig. 3 in which its under side is made on a straight line or flat. The member 11 is in the form of an annular ring, and in either of the constructions shown, the inner lower edge of the bottle receiving opening thereof is yielding, by reason of the inclined inner face *c* upon which the bottle rests. In this arrangement, air to the bottle passes from outside of the cooling chamber, because the outer surface of bottles are never made a true circle, and are more or less rough, leaving air spaces or passages between the bottle and the true annular and smooth face *c* of the member or ring 11. If desired, however, the face *c* of the ring 11 may be provided with one or more transverse air passages or grooves *d*.

A suitable faucet B communicates with the interior of the cooling or ice chamber 3 for drawing off water caused by the melting ice.

Having thus described my invention, what I claim and desire to secure by Letters Patent is:

1. In an inverted bottle cooler, the combination with an inclosing casing, a liquid receiving receptacle therein having an open top, a cover for the inclosing casing, the cover having an opening registering with the opening in said liquid receptacle, the-

top of the liquid receptacle ending approximately at the wall of the cover opening, of an annular member at the junction of the cover opening and the liquid receptacle opening and resting upon both the cover and the said receptacle, and an inverted bottle resting upon the closing member and holding it in contact with the walls of the cover opening and said liquid receptacle opening, the mouth of the bottle projecting into the said liquid receptacle. 45

2. In an inverted bottle cooler, the combination with an inclosing casing, a liquid receiving receptacle therein, a cover for the inclosing casing, said cover and liquid receptacle having registering openings, the wall of the cover opening having a recess in approximately the same plane as the top of the liquid receptacle, of a closing member resting within the recess and upon the open top of the liquid receptacle, and an inverted bottle resting upon the closing member and holding it in contact with the walls of the cover and the top of the liquid receptacle, the mouth of the bottle projecting into the said liquid receptacle. 55

3. In an inverted bottle cooler, the combination with an inclosing casing, a liquid receptacle therein, a cover for said casing, the cover and liquid receptacle having registering openings, of a closing member resting upon the wall of the cover opening and having an annular recess receiving the top of the liquid receptacle, and an inverted bottle resting upon the closing member and holding it in contact with the walls of both the cover and the liquid receptacle. 60

In testimony whereof I hereunto affix my signature in the presence of two witnesses.

WILLIAM E. PATNAUDE.
